UNITED STATES PATENT OFFICE.

WILLIAM A. MATYK, OF CEDAR RAPIDS, IOWA.

CAP.

1,386,890.

Specification of Letters Patent Patented Aug. 9, 1921.

Application filed November 12, 1920. Serial No. 423,601.

To all whom it may concern:

Be it known that I, WILLIAM A. MATYK, a citizen of the United States, residing at Cedar Rapids, in the county of Linn and State of Iowa, have invented certain new and useful Improvements in Caps, of which the following is a specification, reference being had therein to the accompanying drawing.

10 This invention relates to certain new and useful improvements in caps, and more particularly to what is known in the art as dust or boudoir caps, the object being to provide a cap formed of paper and so constructed 15 that it can be manufactured very cheaply so that when it becomes soiled, it can be thrown away.

Another object of the invention is to provide a cap with an elastic band for holding 20 the same firmly in position on the head, the band being so constructed and arranged that it will bind the cap without any unnecessary pressure.

Other and further objects and advantages 25 of the invention will be hereinafter set forth and the novel features thereof defined by the appended claims.

In the drawings,

Figure 1 is a perspective view of a cap 30 constructed in accordance with my invention;

Fig. 2 is a vertical longitudinal section through the cap;

Fig. 3 is a plan view of the blank from 35 which the band of the cap is formed;

Fig. 4 is a plan view of the body of the cap;

Fig. 5 is a perspective view of the elastic strap and non-elastic band;

40 Fig. 6 is a section taken on line 6—6 of Fig. 2; and

Fig. 7 is a detailed enlarged section through a portion of the cap.

In carrying out my invention I cut an 45 oval shaped piece of paper to form the body 1 of the cap and as herein shown I employ crape paper for this purpose. I then cut off one end portion and turn the end back to form a hem 2 and arrange within the ends 50 of the hem reinforcing members 3 which are square shaped pieces of paper bent back upon themselves and secured within the hem by the stitching.

I then cut from a sheet of paper a blank 4 as shown in Fig. 3 which is oblong in shape 55 having its ends scalloped which is folded on a line indicated by 5 and the ends stitched as shown, the longitudinal edge being secured to the curved end 7 of the blank 1 by stitching 8, the band being placed within 60 the body and stitched and then turned upwardly as clearly shown in the drawing.

An elastic strap 9 is then forced through the hem 2 of the body, the ends passing through the reinforcing members 3 so as to 65 prevent the hem from being torn. The free ends of the elastic strap 9 are then passed through openings formed in a non-elastic strap 10, the ends being reinforced 70 as shown at 11. Knots 12 are then formed in the end of the elastic strap and the strap is then placed between the band 4 and the body of the cap.

The body of the cap is gathered as shown at 13 and plaited as shown at 14 to give it a 75 crown effect so that it will be of a proper shape to fit over the head of a woman.

By constructing a cap in this manner a highly ornamental dust or boudoir cap is formed of crape paper which can be used 80 either as a dust or a boudoir cap.

What I claim is:—

1. As a new article of manufacture, a paper cap comprising an oval shaped body gathered longitudinally and transversely to 85 form a substantially hemispherical crown, one end of said body being provided with a hem, a band secured to the other end of said body and extending upwardly therefrom and a strap arranged under said band having 90 an elastic cord extending through the hem of said body and connected to the free ends of said strap.

2. As a new article of manufacture, a dust cap formed of a body gathered to form a 95 substantially hemispherical crown, a band secured to the inside of said crown and extending upwardly around substantially half of the crown, a hem formed around the other half of the crown having reinforcing members at its ends, an elastic cord arranged within said hem and a band having its free end connected to the ends of said cord adapted to be arranged under said band.

3. As a new article of manufacture, a 105 paper dust cap comprising a body gathered

longitudinally and plaited transversely, one end of said body having a hem provided with reinforcing members at its ends, a band secured to the under side of said body and extending upwardly substantially parallel with the body on the outside thereof, an elastic cord disposed within said hem having its ends

working through the reinforcing members and a strap of non-elastic material disposed between said band and body having its ends connected to the free ends of said cord. 10

In testimony whereof I hereunto affix my signature.

WILLIAM A. MATYK.
